(57) **CLAIM**

We claim the ornamental design for an exhaust heat recovery apparatus for automobiles, as shown and described.

DESCRIPTION

FIG. 1 is a perspective view of an exhaust heat recovery apparatus for automobiles, showing a first embodiment of our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of an exhaust heat recovery apparatus for automobiles, showing a second embodiment of our new design;

FIG. 9 is an elevational front view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof; and,

FIG. 15 is a perspective view of the exhaust heat recovery apparatus for automobiles, showing a use state thereof.

The features shown in broken lines in the drawings depict environmental subject matter only and form no part of the claimed design.
